UNITED STATES PATENT OFFICE.

WILLIAM H. DOBLE, OF QUINCY, MASSACHUSETTS, ASSIGNOR OF ONE-FOURTH TO PNEUMATIC SCALE CORPORATION, LIMITED, OF QUINCY, MASSACHUSETTS, A CORPORATION OF MAINE.

SHIPPING-CASE.

1,208,301.

Specification of Letters Patent. Patented Dec. 12, 1916.

Application filed May 31, 1916. Serial No. 100,758.

To all whom it may concern:

Be it known that I, WILLIAM H. DOBLE, a citizen of the United States, residing at Quincy, county of Norfolk, State of Massachusetts, have invented a certain new and useful Improvement in Shipping-Cases, of which the following is a specification, reference being had therein to the accompanying drawings.

10 The invention relates to an improvement in shipping cases.

It has special reference to a shipping case which is intended to be returned to the shipper to be again used. It has been found 15 sometimes that after the shipping case has been received at its destination with the filled packages and before it is returned to the shipper that it has been improperly used as, for instance, as a receptacle for refuse 20 material such as rubbish or ashes or other material for which the shipping case was not intended to be used and which soils the interior of the case so that when it is finally returned to the shipper it is either entirely 25 ruined for its proper purpose or else considerable labor and expense has to be incurred in cleaning and renovating it.

The object of the present invention is to 30 so construct the shipping case that after the merchandise has been removed at its destination it will be practically impossible to use the case for such improper purposes as have been mentioned, or, at any rate, that it can not be so used without such inconvenience 35 that there will be no temptation for such misuse.

The invention consists in forming the case with a drop bottom provided with locking mechanism which normally retains the bottom 40 fastened in place while the cover is closed but which is unlocked by the act of opening the cover so that if the shipping case is lifted from the floor or other support after the cover is raised or partially opened, 45 the bottom will automatically drop and allow the contents of the case to fall out.

The invention is especially intended for 50 application to a shipping case formed with an inner and an outer wall spaced apart from each other and having the panels hinged together in such manner that the case when emptied may be folded into compact form to be returned to the shipper, and the drawings illustrate the invention as applied 55 to a shipping case of that character, al-

though it is not intended to limit the invention either to a folding shipping case or to a case formed with inner and outer wall plates.

The invention will be fully understood 60 when taken in connection with the accompanying drawings and the novel features thereof will be clearly defined in the claims in the close of this specification.

In the drawings, Figure 1 is a top plan 65 view of a shipping case embodying the invention, the cover being broken away at one of the rear corners. Fig. 2 is a bottom plan view looking up from beneath, the bottom panel being partly broken away at two corners and one corner being partly in section. Fig. 3 is a side elevation of a shipping case embodying the invention, the top being 70 closed and the bottom also closed and locked, the side panel being partly broken away to 75 show the locking mechanism for the bottom. Fig. 4 is a section on line 4-4 of Fig. 3. Fig. 5 is a side elevation viewed from the same side as Fig. 3 but showing the cover 80 partly raised and the bottom unlocked and dropped. Fig. 6 is a section on line 6-6 of Fig. 3. Fig. 7 is a bottom plan view looking up from beneath one of the rear corners of the case.

Referring now to the drawings A is the 85 top panel or cover, B is the bottom panel, C is the rear panel, D the front panel, and E and F the two opposite side panels of the shipping case.

Each panel is composed of an inner plate 90 1, an outer plate 2, and an intermediate corrugated plate 3 which contacts alternately with the inner and outer plates and is employed for strengthening and stiffening the panel. 95

The top panel A has a hinged connection 4 at its rear edge with the rear panel C, and the front panel D at its lower edge has a hinge connection 5 with the front edge of the bottom panel B. Preferably the front 100 and rear panels have hinged connections with the two opposite side panels to permit collapsing or folding of the four vertical panels of the shipping case when the top and bottom panels are opened but that forms 105 no part of the present invention.

The front edge of the panel A is intended to be locked to the top edge of the front panel D in any suitable manner which permits of its being unlocked. In the form of 110

construction shown the front edge of the top cover A is formed with an offset portion 6 which, when the cover is closed, engages the upper end 7 of the front panel D. The 5 cover A is formed with a shoulder portion 8 and the upper end of the front panel D is formed with a hook portion 9, said hook portion 9 and shoulder portion 8 being adapted to be engaged by a sealing clip 10 to fasten the cover closed. Said sealing clip 10 may be bent or broken to unlock the cover.

The upper edge of the side panel E has a vertical drop 11 somewhat in front of its rear edge, and the side panel F also has a similar drop. From the bottom of said drop 11, the top edge 12 of the side panel E extends horizontally to the rear edge of said panel.

The portion of the top or cover panel A 20 from its front edge to the beginning of the drop 11 is made of a width to form a close fit between the side panel E and its opposite side panel F and the rear part of said cover panel A is widened out, being formed 25 with a lateral extension 13 on its two opposite edges to lap over onto the upper edge of the portion 12 of the side panel E and the corresponding portion of the opposite side panel F.

30 The lower edge of the side panel E is formed at its rear part with a raised portion 14 connected with the forward portion of the bottom edge of said side panel by a riser 15, said elevated portion 14 and riser 35 15 being preferably of the same dimensions and corresponding location as the portions 12 and 11 at the top edge of said panel. The opposite side panel F has its lower edge constructed in a similar manner to the 40 lower edge of the panel E.

The rear part of the bottom panel B is formed with lateral extensions 33 corresponding with the lateral extensions 13 of the top panel. The said lateral extensions 45 13 lap onto the lower edges of the side panel E and its opposite panel F while the front narrower portion of the bottom panel fits up between the said side panels.

50 The lower edge of the panel E is closed with a channel member 16 which is offset to conform to the rise 15 in the inner and outer plates of said side panel. A bell crank shaped dog 17 is pivoted between the inner and outer plates of the side panel E by a 55 pin 34. Said dog has one arm 18 whose under side is engaged by the free end of a spring 19, the other end of said spring being secured at 20 to a block 21 which may be fastened to the inside of the panel E. 60 The other arm 22 of said dog extends down through a slot 23 in the lower face of the panel member 16 and is formed with a toe 24.

65 A channel member 25 closes the rear edge of the bottom panel B, being inserted be-

tween the inner and outer plates thereof. Channel members 27 also close the two opposite edges of the bottom panel B.

A bar 26 extends crosswise from one side edge to the other of the bottom panel B 70 and is formed with a slot 28 into which the foot of the arm 22 of the dog extends. The wall of said slot 28 is in part undercut to form an overhanging flange 29 with which the toe 24 of said dog is adapted 75 to engage when the bottom panel is in closed position as shown in Fig. 3. The spring 19 which presses up against the under side of the arm 18 is under tension and tends to press up said arm 18 and thereby to disengage 80 the toe of the dog from the flange 29.

A bar 30 lies loosely in a vertical position in one of the spaces between the corrugated plate 3 and one of the face plates of the side panel E, the lower end of said bar 85 resting upon the upper side of the arm 18 of the dog and the upper end extending up a short distance above the upper edge of the rear portion 12 of said panel E where it is engaged by the under side of the lateral extension 13 of the cover panel A. A pin 31 secured to said bar 30 projects laterally through a vertically elongated slot 32 in one of the wall plates of the panel E, preferably through the inner wall plate 1 90 because it is preferred to have the outer wall plate entirely unperforated. This elongated vertical slot allows a limited range of vertical movement of the bar 30. The side panel F at the opposite side of the box from the panel E is also provided with a dog 95 and an operating bar and spring similar to the dog 17, bar 30, and spring 19 already described adapted to form locking engagement with the flange 29 where it extends beneath the lower edge of said side panel F. When the cover A is turned up on its 100 hinge as shown in Fig. 5 the bars 30 are free to move upward and thereby to permit the dog 17 to be turned on its pivot by the upward pressure of the spring 19 and disengage the toe 24 of each of the dogs from the flange 29. When the cover panel A is 105 closed as in Fig. 3, the extension portion 13 pushes down on the upper ends of the bars 30 thereby holding the dogs 17 in a position where the toe 24 of each dog is engaged in the slot beneath the flange 29 and thereby locks the bottom panel B so 110 that when the box is lifted from the floor the bottom panel B will still remain closed, even though the sealing clip 10 is removed provided the cover is not lifted after the clip is removed. When the cover is lifted, the dog will be turned and thus disengaged 115 from locking position but the bottom panel will still remain closed, although unlocked until the box is lifted. As soon as the box is lifted after the cover is opened, the rear end of the bottom panel will drop down 120

125 130 135 140 145 150

as shown in Fig. 5 thereby allowing any contents of the box to drop out through the bottom.

All of the six panels composing the shipping case preferably have the open space between the inner and outer plates of each edge closed by suitable channel plates.

What I claim is:

1. A box having a drop bottom, means for normally retaining said drop bottom in a closed position, a cover for the top, and means controlled by said cover in its closed position to retain said bottom locking means in operative position.
2. A box having a cover, a drop bottom, means for locking said drop bottom in a closed position, means tending to release said bottom locking mechanism, and intermediate mechanism controlled by the cover in its closed position to hold said releasing mechanism in restraint, said restraining mechanism being released by the opening of the cover.
3. A box having a cover, a drop bottom, locking mechanism mounted within two opposite side walls of the box and projecting down through the lower edge of said side walls, said bottom being slotted to receive the said downwardly projecting lock mechanism and having coöperating means to be engaged by said locking mechanism whereby the said bottom is locked in closed position, means which tend to release said locking mechanism when the cover is open, and means controlled by the cover in its closed position to retain said locking mechanism in locking engagement with said bottom.
4. A box having front and rear walls, two opposite side walls, a drop bottom hinged on one edge to said front wall, a cover hinged to the upper edge of said rear wall, each of the said two side walls having pivoted therein a bell crank dog having one arm which

extends down through a slot in the lower edge of the wall in which it is mounted, the bottom being slotted on its inner face and having a socket member which is adapted to be engaged by a tooth on the downwardly projecting arm of said dog to lock said bottom to the side wall, means which normally hold said dog in a disengaged position with relation to the socket member in said bottom when the cover is open, and intermediate mechanism engaged by said cover which, when the cover is closed, holds said dog in locking engagement with the bottom and which is released to permit the dog to be disengaged when the cover is opened.

5. A box having front and rear walls, two opposite side walls, a drop bottom hinged on one edge to the front wall, a cover hinged to the upper edge of said rear wall, a dog pivotally mounted in each of said side walls having one arm which extends down through the lower edge of the wall in which it is mounted and into a slot in the bottom panel, a coöperating member in said slot with which said dog is adapted to engage to lock the said bottom in closed position, a vertically slideable member mounted in said side wall, the lower end of said slideable member engaging with said dog, the upper end being engaged by the said cover, and tension means which tends to unlock said dog and lift the slideable member, said unlocking mechanism being rendered inoperative by the downward pressure of the cover in closed position and being rendered operative when the cover is raised to release the pressure.

In testimony whereof I affix my signature, in presence of two witnesses.

WILLIAM H. DOBLE.
